[57] CLAIM

The ornamental design for a cassette for holding dental pressure measuring sheet, as shown and described.

DESCRIPTION

FIG. 1 is a perspective view of a cassette for holding dental pressure measuring sheet showing our new design;

FIG. 2 is a front elevational view thereof;

FIG. 3 is a rear elevational view thereof;

FIG. 4 is an edge view thereof from the top of FIG. 2; FIG. 5 is an edge view thereof from the bottom of FIG. 2;

FIG. 6 is an edge view thereof from the left of FIG. 2; FIG. 7 is an edge view thereof from the right of FIG. 2; FIG. 8 is a view similar to FIG. 1 but showing the cassette open for the insertion or removal of a said sheet which is shown in broken lines;

FIG. 9 is a cross-sectional view thereof in a vertical plane perpendicular to the plane of FIG. 2; and, FIG. 10 is a cross-sectional view thereof in a horizontal plane perpendicular to the plane of FIG. 2.
